US0D1057449S

(12) **United States Design Patent** (10) **Patent No.:** **US D1,057,449 S**
(45) **Date of Patent:** **** Jan. 14, 2025**

(54) **ERGONOMIC CHAIR**

(71) Applicant: **Guangdong Shengyi Furniture Group Co., Ltd.**, Foshan (CN)

(72) Inventor: **Huilin Gan**, Jiujiang (CN)

(73) Assignee: **Guangdong Shengyi Furniture Group Co., Ltd.**, Foshan (CN)

(**) Term: **15 Years**

(21) Appl. No.: **29/941,828**

(22) Filed: **May 13, 2024**

(51) LOC (15) Cl. **06-01**

(52) U.S. Cl.

USPC **D6/366**
